J. Lowell Gibson, Dayton, Ohio, assignor to General Motors Corporation, Dayton, Ohio, a corporation of Delaware

Application June 17, 1937, Serial No. 69,884

Term of patent 7 years

To all whom it may concern:

Be it known that I, J. Lowell Gibson, a citizen of the United States, residing at Dayton, in the county of Montgomery and State of Ohio, have invented a new, original, and ornamental Design for Drinking Water Cooler Fountains, of which the following is a specification, reference being had to the accompanying drawing, forming part thereof.

In the drawing:

Fig. 1 is a view in perspective of a drinking water cooler fountain showing my design;

Fig. 2 is a rear view in elevation of the same; and

Fig. 3 is a top plan view of the same.

I claim:

The ornamental design for a drinking water cooler fountain as shown.

J. LOWELL GIBSON.
